(57) **CLAIM**

The ornamental design for a valve actuator, as shown and described.

DESCRIPTION

FIG. 1 is a top perspective view of a valve actuator showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines shown in the figures are included for the purpose of illustrating portions of the valve actuator and form no part of the claimed design.
